CLAIM

The ornamental design for a pet bath, substantially as shown.

DESCRIPTION

FIG. 1 is a perspective view taken from the top, one side and one end of a pet bath showing my new design; FIG. 2 is a top plan view thereof;

FIG. 3 is an elevational view taken from the end opposite that shown in FIG. 1;

FIG. 4 is a bottom plan view thereof;

FIG. 5 is an elevational view taken from the side opposite that shown in FIG. 1; and

FIG. 6 is a cross sectional view taken on line 6—6 of FIG. 2.
